CLAIM

The ornamental design for a computer display with graphical user interface for a pharmacovigilance tool, as shown and described.

DESCRIPTION

The sole FIGURE is a front view of a computer display with graphical user interface for a pharmacovigilance tool. The broken line drawings of a computer display, text, numbers and other graphic elements form no part of the claimed design.

The perimeters of the underlying computer display and graphical user interface are understood to be flush.

1 Claim, 1 Drawing Sheet
